UNITED STATES PATENT OFFICE.

HUGO REHMANN, OF MÜLHEIM-ON-THE-RUHR, GERMANY.

DEVICE FOR CHARGING FURNACES, GAS-GENERATORS, &c.

No. 853,420.

Specification of Letters Patent.

Patented May 14, 1907.

Application filed August 24, 1906. Serial No. 331,943.

To all whom it may concern:

Be it known that I, HUGO REHMANN, civil engineer, a subject of the German Emperor, and a resident of Mülheim-on-the-Ruhr, 5 Bürgerstrasse 10, Germany, have invented certain new and useful Improvements in Devices for Charging Furnaces, Gas-Generators, and the Like, of which the following is a specification.

The invention relates to a device for charging material into furnaces. It is especially suitable for charging coal into furnaces, gas generators and the like.

The features of the invention consist firstly 15 in the novel combination, secondly in the novel arrangement; and thirdly in the novel formation of the individual parts.

The combination is new in so far as the 20 hopper which can be closed at the top in a well-known manner is provided at its outlet in the lower part with a closing device; further directly in the hopper itself there is a crushing device arranged for the coal, and under the outlet, which is from time to time 25 closed; a novel distributing device is arranged for the material falling into the furnace. The new arrangement of the parts lies chiefly in the accommodation of the crushing mechanism in the upper part of the hopper itself, 30 and further in the situation of the cut-off for the hopper outlet working up and down on the shaft of the distributor.

The new formation of the individual parts 35 is shown in the following description, having reference to the accompanying drawings.

Figure 1 is a partial vertical section through the new device. Fig. 2 shows in vertical section a special formation and arrangement 40 of the crushing mechanism. Fig. 3 shows in vertical section an enlarged view of the cut-off for the outlet of the hopper in the closed position. Figs. 4 and 5 are enlarged representations of the individual parts of the distributing mechanism.

The hopper of circular cross section consists of the fixed upper part 1, the rotatable middle part 2 and the fixed lower part 3. The upper part 1 and therefore the whole 45 hopper can be closed by means of the cover 4 which dips in well-known manner into the water-seal 5. The upper part 1 dips with its wall 6 into the water-seal 7 of the middle part 2, so that between the parts 1 and 2 of the hopper a perfect seal against the escape of 50 gas is formed. In the same way the middle part 2 dips with its flange 8, into the water-

seal 9 of the lower part 3, so that also between parts 2 and 3 a perfect seal against the escape of gas is formed.

The turning of the middle part 2 can be accomplished by means of any suitable contrivance. In the example given in Fig. 1 this turning is produced by means of a cog-wheel 10 fitted on the outer circumference of the middle part 2. A ratchet-wheel 11 engages 60 with the cog-wheel 10, and is made to rotate by means of the clutch 12, and the rods 13 and 14 from the driving mechanism 15.

Inside the upper part 1 of the hopper the crusher 16 is fitted. The crusher 16 is fixed 70 on the middle part 2 which turns on the ball bearings 20. The crusher is provided on its working face with projections 17 in the form of ribs, ledges, or teeth. The crusher 16 can be made conical as shown in Fig. 1, where it 75 is situated concentrically to part 1. The crusher 16 can however also be made cylindrical and arranged eccentrically to part 1; as shown in Fig. 2. In both cases the crusher has a circular cross section; it can 80 however also be constructed of polygonal form; or in one or more places be provided with eccentric projections.

The rotation can, as in the example given in the drawings, be brought about through 85 the breaker; the arrangement however can also be made, that part 1 rotates round the breaker, while the latter remains still or if necessary rotates in the same or the opposite sense. In each case the charging material 90 will be crushed, before it falls into the lower part of the hopper and from here into the furnace.

The inside wall of the upper part 1 possesses an appropriate funnel shaped declivity 95 or construction 18, and is also like the crusher 16 provided with projections in the form of ribs, ledges, or teeth, by means of which the crushing of the material is accelerated, and carried out in an efficient manner. 100 In order to prevent the escape of gas from the furnace during the charging the hopper can be closed at times not only from above, but also at its exit underneath. To the rotatable middle part 2 is attached at right angles the axle or shaft 21, on the lower end of which the distributor 22 is situated. On the shaft 21 is situated the gas cut-off 23 which can be moved up and down aided by the suitably wide boring 29. The part 23 is 105 moved by means of the lever 25 pivoted at 24; the lever can be provided with a counter-

poise 26, so that the cut-off 23 ordinarily remains open.

The hopper when charging is closed above by means of the cover 4 (Fig. 1.): the cut-off 23 is in this case opened.

If the hopper is to be refilled the cut-off 23 which has a suitable double conical form is brought down with its surface 27 on to the edge 28 of the outlet. The projection 30 of the shaft or axle 21, which in consequence of the rotation of part 2 itself turns and rotates the distributor 22, engages with the surface 31 of the cut-off 23. In this way the best possible gas-tight closure is effected, without the easy movement of the part 23 up and down, or the rotability of the shaft 21, and therefore the distributor 22, being hindered. After the lowering of the cut-off 23 the cover 4 is raised, and the charging of the hopper accomplished. After closing again with the cover 4, part 23 is again raised by means of the lever 25 (Fig. 1.) and in this position is held by the weight 26 until the next charging. In this way at each recharging only that volume of gas can escape which is inclosed between the cut-off 23 and the cover 4.

Under the outlet of the hopper the distributing device 22 is arranged. This distributor rotates in exact agreement with the middle part 2 because it is in rigid connection with it through its axle or shaft 21. The distributor 22 has the form of a cone, which is cut off in a plane oblique to its vertical axis. The lower surface 32 of the distributor is therefore at all points of its circumference situated at a different distance from the point of the cone; on the outer surface of the cone are also formed slanting surfaces of different lengths, which all possess the same angle of inclination. The object of this construction is to bring about a perfect distribution of the falling material.

It is obvious that the construction of the new charging device, shown in the drawing may be modified without leaving the scope of the invention.

What I claim as my invention, and desire to secure by Letters Patent is:—

1. In a device for charging furnaces, gas generators and the like, the combination of a hopper with a closable top, means for crushing the coal in this hopper, a device for periodically closing the lower part of the hopper, and a device for distributing the coal at the outlet, substantially as described and for the purpose specified.

2. In a device for charging furnaces, gas generators and the like the combination of a hopper divided into three parts, and closable at the top, projections on the surface of the upper fixed part of the hopper, a crusher fixed on the rotatable middle part of the said

hopper, projections on the surface of the crusher, means for moving the middle part of the hopper, means for periodically closing the lower fixed part of the hopper, and means for distributing the crushed coal at the outlet, substantially as described, and for the purpose specified.

3. In a device for charging furnaces, gas generators, and the like, the combination of a hopper divided into three parts with a closable top, projections on the inner surface of the upper fixed part of the hopper, means for moving the rotatable middle part of the hopper, a rotatable crusher of eccentric form in the upper part of the hopper, projections on the surface of the crusher, means for periodically closing the lower part of the hopper, and means for distributing the crushed coal at the outlet, substantially as described, and for the purpose specified.

4. In a device for charging furnaces, gas generators and the like, the combination of a hopper divided into three parts, and closable at the top, a device for crushing the coal in this hopper, an axle fixed to the rotatable middle part of the hopper, a distributing device on the lower end of this axle, a closing device in the lower part of the hopper moving vertically on the said axle, means for moving the closing device, and means for attaining a gas-tight seal between the closing device in the lowered position, the outlet of the hopper, and the said axle, substantially as described, and for the purpose specified.

5. In a device for charging furnaces, gas generators and the like, the combination of a hopper divided into three parts and closable at the top, a device for crushing the coal in the hopper, a device for periodically closing the lower part of the hopper, an axle on the rotatable middle part of the hopper for guiding the said closing device and for bearing and moving the distributing device, means for moving the middle part of the hopper with the crushing mechanism and the distributing device, a closing surface at the lower end of the bore of the closing device, a distributor in the form of a cone truncated obliquely to its vertical axis fixed on the lower end of the said rotatable axle, and slanting surfaces of different lengths on said distributor having the same angle of inclination, substantially as described, and for the purpose specified.

In testimony whereof I have hereunto signed my name this fourth day of August 1906, in the presence of two subscribing witnesses.

HUGO REHMANN.
